APPARATUS DESIGNED FOR THE SUCCESSIVE EXHIBITION OF DIORAMAS

Philippe Alexis Jean Carré and Jacques Louis
Alexis Maurice Carré, Paris, FranceApplication June 2, 1937, Serial No. 146,046
In France June 18, 1936

10 Claims. (Cl. 40—36)

The present invention relates to an apparatus for successively exhibiting a series of dioramas by an arrangement which is continuous and automatic in its operation so as to bring another diorama into position to be viewed after a preceding one shall have been exhibited.

A further object is to provide dioramas which are pliable and foldable.

Again, it is an object to provide an exhibiting apparatus having a storage space for the folded dioramas, an exhibiting chamber having an opening, and means for bringing the dioramas from the storage space into the exhibiting chamber, means to unfold the dioramas for exhibition purposes and thereafter re-fold them and return them to the storage space.

In the drawings:

Fig. 1 shows a side elevation (parts being in section) of the apparatus according to the invention;

Fig. 2 is a plan view of same;

Fig. 3 shows the back side of the apparatus the wall of which has been removed;

Fig. 4 is a detail view, similar to Fig. 2, but showing a modification of the invention;

Fig. 5 is a detail perspective view of a portion of the apparatus.

Fig. 6 is a detail horizontal section taken just above the plane containing the elements 14.

According to Figs. 1, 2 and 3, the apparatus is made of a box 1, the front wall 2 of which is provided with an opening 3. This box has two horizontal partitions 4, 5 dividing same into three compartments 6, 7, 8. The compartment 7 is used as a storage space for the folded dioramas 9a, 9b, . . . 9f, and the compartment 8 as an exhibition chamber containing an unfolded diorama 10.

The dioramas are made of a front frame 11 and a back plate 12 connected by the means of the folding (bellows-like) part 13. To the said frame 11 and plate 12 are fixed one or several intermediary planes 12a representing the scenery, the said planes being parallel or not to the end planes, and are supported by being fastened to the articulated or folding part 13. The intermediate planes are adapted to assume the desired positions when the diorama is unfolded by opening the plate 12 and the frame 11, and to be folded again when the plate 12 and the frame 11 are brought near one another.

On the frame 11, near the vertical edges, are fixed two hooks 14 directed towards the back face.

On the vertical side walls of the box are

mounted the pairs of sprockets 15, 16, 17, 18, 19 and 20 on which run two chains 21 driven by the said sprockets. The chains are operated by any suitable known means which will drive a pair or pairs of the sprockets. Each chain 21 has a finger 22 directed towards the inside of the box and designed to engage the hooks 14 borne by the frame 11 of the diorama 9a, so as to drive same together with the chains 21. The back plate 12 of the dioramas has on its sides notches 23. Flat springs 24, fixed on the box are provided at their free end with a vertical rod 25 coming into cooperation with the said notches 23 when the diorama is in the exhibition chamber 8, the rods 25 resting then against the fore face 15 of the back plate 12 and thus preventing this last plane from moving forward. On the box are also fixed the spring blades 26 the free end of each of which is bent so as to present a vertical supporting surface. Other spring blades 27 are 20 furthermore fixed on the front wall 2 of the box. Under the lower face of the horizontal partition 5 is arranged an elastic hook 28. A curtain 29, provided with a spring, not represented in the drawings, which tends to roll it 25 up, is mounted above the opening 3 of the wall 2 of the box, the said curtain when unrolled concealing the said opening. The bar 30 of the curtain is connected at its ends to hooks 31 sliding in the guideways 32 on the side walls of the 30 box 1. Fingers 33, borne by the chains 21, come into contact with the said hooks in order to unroll the curtain 29 and thus to conceal the opening 3. On the other hand, the hooks are held in the lowest position to which they have been 35 brought by the fingers 33 by means of hooks 34 hinged at a point 34a and provided with a tail member 35 on which the fingers 33 press to disengage the hooks 34 and 31. The hooks 34 are moved to their original position by the action of 40 the spring blades 36.

The horizontal partition 4 is provided in the vicinity of the front wall of the box with a surface 37 made of an elastic material, spongy rubber for instance, covered or not with a felt strip 38 making a slight projection 39 above the level of the upper face of the partition 4.

The operation is as follows: The two chains 21, each of them being driven by one or several sprockets on which they are running, receive a 50 continuous motion and, in the position shown in Fig. 1, the fingers 22, fixed to the chains 21, are on the vertical part of the chain between the pinions 15 and 16, and above the level of the hook 14 of the diorama 9a contained in the 55

storage space 7. By containing their movement, fingers 22, driven by the chains, come into engagement with the hooks 14 of the diorama 9a. The diorama rises and is carried up into the exhibition chamber 8 until the chains 21, running over the sprockets 18, assume another direction. The fingers 22 of the chains 21, being still engaged in the hooks 14 of the diorama, drive the same towards the front of the box. On the beginning of its horizontal motion, the frame 11 of the diorama opens the springs 24, which held the back plate of the diorama 12, which was in position. The back plate 12 of this last diorama is thus freed from springs 24 as the rods 25 no longer are held against it and it moves forward, pushed by the frame of the following diorama 9a. When the frame 11 of the diorama 9a has gone beyond the springs 24, these return to position and when the back plate of the same diorama contacts the springs these last engage the notches 23 of the plate and hold it by means of the rods 23. During the continuation of their movement, the chains 21 with their fingers 22 still in engagement in the hooks 14 drive forward the frame 11 of the diorama 9a, and since the back plate of the same is retained by the rods 23, the diorama is thus opened. Shortly before the fingers 22 of the chains 21 reach the pinions 17, the back plate of the diorama 10 passes beyond the fore edge of the horizontal partition 5, and this diorama falls into the lower storage space. At the same time, the frame 11 of the diorama 9a passes the spring blades 26 which close again behind it and remain closed in order to prevent the diorama from folding backward. When the fingers 22 of the chains 21 have reached the pinion 17, the chains run in another direction, disengage the fingers from the hooks 14 and continue their way. While falling into the storage chamber or space, the diorama 10 contacts the springs 27, which are very weak. These springs cause the upper part of the diorama to swing slightly towards the rearmost part of the storage space. Owing to the sprockets 18, the chains 45 changing their direction act through the fingers 22 on the frame 11 of the diorama having just fallen down, and pushing same cause the whole of the dioramas contained in the storage space to move backward. At the end of this motion, the frame 11 of the diorama just fallen down comes in engagement at its upper part with the hook 28. This completes one step or cycle of operation of the apparatus. In order to allow this hook to pass easily over the upper edge of the back plate 12, the plate is preferably provided with a notch 28a. The diorama is furthermore maintained in an upright position at its lower position by the slight projection 39 of the felt 38.

In order to prevent the changes of dioramas being seen from outside, the opening 3 of the box 1 is advantageously closed by a curtain in the course of the operation. For this purpose, the fingers 33 are fixed to the chains at such a point that they meet with the hooks 31 shortly before or at the moment at which begins the folding of the exhibited diorama. The said fingers 33 come into engagement with the hooks 31 fixed to the rod 30 of the curtain 29 at the moment that the chains are running over the pinions 17. Upon downward movement, the fingers 33 lower the curtain and when they arrive at their lowest position, the hooks 31 engage the hooks 34. Owing to the change of direction of the chains running over the sprockets 18, the fingers 33 are loosened

from the hooks 31, which are still held by the hooks 34. During the continuation of their movement, the fingers 33 press on the tail member 35 of the respective hook 34 at the moment when the new diorama 9a is fully unfolded. The hooks 34 are thus disengaged from the hooks 31, and the curtain rolls up under the action of its spring to exhibit the diorama 9a (the next one in order).

According to a modification represented in Fig. 10 4, the exhibition chamber is provided with two pairs of vertical U-shaped slides 40, 41 the lower end of which is made flush with the upper part of the partition 5, and of a length approximately equal to the height of the dioramas. The distance between the slides in each pair and between the two pairs is such that the side edges of the frame 11 and of the back plate 12 engage the said slides when the diorama is going up from the storage space into the exhibition chamber. The pair of slides 40 is connected to the back wall of the box by means of elastic devices, such as springs 43. The pair of slides 41 is connected to the pair of slides 40 by similar springs 44. Hooks 45 are also arranged to prevent the pair of slides 41 moving forward. The box 1 is also provided with suitable guiding means, not represented, allowing the said slides 40, 41 to run in a parallel direction to the partition 5.

The operation is as follows: When the diorama 9a is engaged by the side edges of both its frame 11 and back plate 12 in the slides, the fingers 22 of the chains 21 drive forward, in the same way as previously, the frame 11 and with same the slides 40. The diorama is opened and the slides 40 reach the position 40a in which they are held by the springs 26. The chains furthermore support a snug acting upon any system of levers, so as to loosen the hooks 45 maintaining the slides 41 at any given position. The hooks 45 being loosened, the springs 44 drive the slides 41 to their position 41a, thus folding the diorama, which then falls down into the store. The same or other fingers operate somewhat later upon another system of levers removing the springs 26 having retained the slides 40 into the front position 40a. Therefore the whole of the two slides return to the starting position and are ready to receive another diorama.

Having now described this invention and in which manner same is to be performed, what we claim is:

1. In apparatus of the character described, a casing having an exhibition chamber provided with an opening to view a diorama when in the exhibition chamber, said casing having a storage chamber, a plurality of foldable dioramas located in folded condition in said storage chamber, means for bringing a folded diorama from the storage chamber into the exhibition chamber, means to unfold the diorama in the exhibition chamber to present it for view through the viewing opening, and means to refold the diorama and return it to the storage chamber.

2. In apparatus of the character described, a casing having an exhibition chamber provided with an opening to view a diorama when in the exhibition chamber, said casing having a storage chamber, a plurality of foldable dioramas located in folded condition in said storage chamber, means for bringing a folded diorama from the storage chamber into the exhibition chamber, means to unfold the diorama in the exhibition chamber to present it for view through the viewing opening.

ing opening, and means to refold the diorama and return it to the storage chamber, a curtain for the viewing opening, means for moving said curtain to uncover said viewing opening while the diorama is in condition for exhibition, and means to draw the curtain over said opening at other times.

3. In apparatus of the character described, a box having a partition dividing it into a storage space and an exhibition chamber, and having a sight opening for the exhibition chamber, a curtain, means continuously tending to maintain the curtain in position to uncover the sight opening, a set of foldable dioramas stored in said storage space in folded condition, an endless conveyor for serially carrying the dioramas in folded condition from the storage space to the exhibition chamber and back to the storage space, means for unfolding the dioramas while in the exhibition chamber for viewing purposes and thereafter refolding the same to be conveyed back to the storage space, and means actuated by said conveyor for drawing the curtain over the sight opening while a diorama is being transferred from the exhibition space to the storage space and another diorama is being made ready in the exhibition chamber.

4. In apparatus of the character described, a box having a partition dividing it into a storage space and an exhibition chamber, and having a sight opening for the exhibition chamber, a curtain, means continuously tending to maintain the curtain in position to uncover the sight opening, a set of foldable dioramas stored in said storage space in folded condition, an endless conveyor for serially carrying the dioramas in folded condition from the storage space to the exhibition chamber and back to the storage space, means for unfolding the dioramas while in the exhibition chamber for viewing purposes and thereafter refolding the same to be conveyed back to the storage space, and means actuated by said conveyor for drawing the curtain over the sight opening while a diorama is being transferred from the exhibition space to the storage space and another diorama is being made ready in the exhibition chamber, said last named means including hooks on the curtain and members on said conveyor to engage said hooks, latches to engage said hooks in their down position to hold the curtain, said latches having means for engagement by said members on further movement of said members to effect a release of said curtain latches.

5. In apparatus of the character described, a casing having a horizontal partition dividing it into a storage space and an exhibition chamber, a set of foldable dioramas in said casing, means to hold dioramas in folded condition in said storage space, said dioramas each including a front frame, a back plate and at least one intermediate frame, and a bellows connecting the front frame and back plate and sustaining the intermediate frames, hooks on said front frame, an endless chain conveyor having elements to engage said hooks for conveying folded dioramas from the storage space to and along the exhibition chamber, and means in the exhibition chamber to engage and restrain the back plate of the diorama while the front frame is being pulled along by said conveyor to open the diorama in the exhibition chamber.

6. In apparatus of the character described, a casing having a horizontal partition dividing it into a storage space and an exhibition chamber,

a set of foldable dioramas in said casing, means to hold dioramas in folded condition in said storage space, said dioramas each including a front frame, a back plate and at least one intermediate frame, a bellows connecting the front frame and back plate and sustaining the intermediate frames, hooks on said front frame, and endless chain conveyor having elements to engage said hooks for conveying folded dioramas from the storage space to and along the exhibition chamber, means in the exhibition chamber to engage and restrain the back plate of the diorama while the front frame is being pulled along by said conveyor to open the diorama in the exhibition chamber, said casing having a window to the exhibition chamber, a curtain for covering said window, and means governed by said conveyor for actuating said curtain in timed relation to cover the window while dioramas are being made ready to exhibit and to uncover the window when a diorama is in condition for exhibition.

7. In apparatus of the character described, a casing having a horizontal partition dividing it into a storage space and an exhibition chamber, a set of foldable dioramas in said casing, means to hold dioramas in folded condition in said storage space, said dioramas each including a front frame, a back plate and at least one intermediate frame, a bellows connecting the front frame and back plate and sustaining the intermediate frames, hooks on said front frame, an endless chain conveyor having elements to engage said hooks for conveying folded dioramas from the storage space to and along the exhibition chamber, means in the exhibition chamber to engage and restrain the back plate of the diorama while the front frame is being pulled along by said conveyor to open the diorama in the exhibition chamber, said casing having a window to the exhibition chamber, a curtain for covering said window, and means governed by said conveyor for actuating said curtain in timed relation to cover the window while dioramas are being made ready to exhibit and to uncover the window when a diorama is in condition for exhibition, said last named means including means continuously tending to withdraw the curtain from over the window, cooperating means on the curtain and on the conveyor for drawing the curtain over the window during a portion of the movement of the conveyor, and means to hold the curtain over the window for a definite period and then upon further movement of the conveyor to release the curtain.

8. In apparatus of the character described, a casing having a horizontal partition dividing it into a storage space and an exhibition chamber, a set of foldable dioramas in said casing, means to hold dioramas in folded condition in said storage space, said dioramas each including a front frame, a back plate and at least one intermediate frame, a bellows connecting the front frame and back plate and sustaining the intermediate frames, hooks on said front frame, an endless chain conveyor having elements to engage said hooks for conveying folded dioramas from the storage space to and along the exhibition chamber, and means in the exhibition chamber to engage and restrain the back plate of the diorama while the front frame is being pulled along by said conveyor to open the diorama in the exhibition chamber, said engaging and restraining means comprising notches in the side of the back plate of the dioramas, spring arms

in the casing to lie in said notches and having rods to engage said back plate, said spring arms being releasable from said back plate upon engagement of the arms by the front frame of a 5 succeeding diorama.

9. In apparatus of the character described, a casing having a horizontal partition dividing it into a storage space and an exhibition chamber, a set of foldable dioramas in said casing, means 10 to hold dioramas in folded condition in said storage space, said dioramas each including a front frame, a back plate and at least one intermediate frame, a bellows connecting the front frame and back plate and sustaining the intermediate frames, hooks on said front frame, an 15 endless chain conveyor having elements to engage said hooks for conveying folded dioramas from the storage space to and along the exhibition chamber, means in exhibition chamber to engage and restrain the back plate of the diorama while the front frame is being pulled along by said conveyor to open the diorama in the exhibition chamber, and means to hold the front 20

frame of the diorama in the exhibition chamber when in its open or unfolded position.

10. In apparatus of the character described, a casing having a horizontal partition dividing it into a storage space and an exhibition chamber, a set of foldable dioramas in said casing, means 5 to hold dioramas each including a front frame, a back plate and at least one intermediate frame, a bellows connecting the front frame and back plate and sustaining the intermediate frames, 10 hooks on said front frame, an endless chain conveyor having elements to engage said hooks for conveying folded dioramas from the storage space to and along the exhibition chamber, means in exhibition chamber to engage and restrain the 15 back plate of the diorama while the front frame is being pulled along by said conveyor to open the diorama in the exhibition chamber, and means to hold the front frame of the diorama in the exhibition chamber when in its open or unfolded position, 20 said last named means comprising yieldable blades.
